UNITED STATES PATENT OFFICE.

VACE E. DENNIS, OF PONY, MONTANA.

CATTLE-GUARD.

1,071,146.

Specification of Letters Patent. Patented Aug. 26, 1913.

Application filed September 30, 1911. Serial No. 652,108.

To all whom it may concern:

Be it known that I, VACE E. DENNIS, a citizen of the United States, residing at Pony, in the county of Madison and State 5 of Montana, have invented a new and useful Cattle-Guard; and I do hereby declare the following to be a full, clear, and exact description of the invention, such as will enable others skilled in the art to which it applies 10 to make and use the same.

This invention relates to a new and useful roller cattle guard.

The object of the invention is to provide an improved device of this nature, adapted 15 for use upon railways, to prevent passing of cattle from one side of a fence or barrier to the other side thereof, by way of the rail-way.

A feature of the invention is the provision 20 of a plurality of tubular rollers having cast iron plugs in their ends, which plugs include steel journal pins, which are mounted in bearings of the frame of the cattle guard.

A further feature of the invention is the 25 provision of wear plates for the journal pins.

The invention comprises further features and combination of parts, as hereinafter set forth, shown in the drawings and claimed.

In the drawings: Figure 1 is a plan view 30 of a roller cattle guard, constructed in accordance with the invention. Fig. 2 is a longitudinal sectional view on line 2—2 of Fig. 1. Fig. 3 is a transverse sectional view on line 3—3 of Fig. 1. Fig. 4 is a detail perspective view of one of the tubular rollers.

Referring to the drawings 1 designates a frame work, which is rectangular in contour, and provided with a pair of transverse bearing beams 2, on which the rails 3 are secured.

Between the rails and the bearing beams, 40 wear plates 4 are disposed, while on the end beams 5 of the frame 1 wear plates 6 are secured. The wear plates 4 and 6 are constructed with downturned elongated 45 flanges 7 and 8, the purpose of which will hereinafter appear.

A plurality of tubular rollers 9 are arranged in the frame. The ends of the rollers, as shown clearly in Fig. 4, are closed by means of cast iron plugs 10, which are annularly recessed as shown at 11, which receive the peripheral portions of the tubular rollers. These plugs are secured in position by means of bolts or other suitable means 50 12. The plugs are provided with steel journal pins 13, which are threaded or otherwise secured in the plug, as shown at 14. These pins are mounted in bearings 15 of the beams 2 and 5, as shown in Fig. 3. The down-turned elongated flanges 7 and 8 act 55 as wear plates for the pins, for the reason that the beams 2 and 5 are constructed of heavy timber or the like, and the bearings 15 therein would become large from the constant movement of the pins in the bearings. 60

From the foregoing it will be noted, there has been produced a novel, simple and efficient roller cattle guard, and one which has been found to be practicable in construction and which will prevent cattle from passing 70 over the crossing.

The invention having been set forth, what is claimed as new and useful is:—

In a cattle guard, a tubular roller, removable caps for the ends of the roller, means 75 for securing the cap in place, each cap having a removable re-placeable screw with a head engaging the inner face of the cap, said screw having a reduced extension portion constituting a pivot adapted to be journaled in a bearing plate, said screw being renewable independent of its cap plate.

In testimony whereof I have signed my name to this specification in the presence of two subscribing witnesses.

VACE E. DENNIS.

Witnesses:

CHARLEY E. DENNIS,
CAREY L. DENNIS.
